UNITED STATES PATENT OFFICE.

ARNE T. PETERSON, OF RACINE, WISCONSIN.

PENCIL-SHARPENER.

No. 873,079.

Specification of Letters Patent.

Patented Dec. 10, 1907.

Application filed February 14, 1907. Serial No. 357,251.

To all whom it may concern:

Be it known that I, ARNE T. PETERSON, residing in Racine, in the county of Racine and State of Wisconsin, have invented new and useful Improvements in Pencil-Sharpener, of which the following is a description, reference being had to the accompanying drawings, which are a part of this specification.

10 This invention has for its object to provide a pencil sharpener of a simple construction which will be of a size and shape convenient for carrying in the pocket and which will be efficient and durable in use.

15 Another object of this invention is to provide a pencil sharpener in which the cutting operation will be made in strokes in the direction of the point of the pencil instead of around the point of the pencil, whereby a 20 more perfect operation is performed without liability of breaking the point of the pencil.

Another object of this invention is to provide such a pencil sharpener with means for reinforcing the pencil point during the sharpening operation to prevent its being broken.

Another object of this invention is to provide such a pencil sharpener with a suitable receptacle for receiving the shavings.

Another object of this invention is to provide a pencil sharpener with a cutter traveling in an arc shaped path, whereby a sharp point will be produced on the pencil without cutting the wood of the pencil at as great a distance from the point as with a cutter traveling in a straight line.

With the above and other objects in view the invention consists in the pencil sharpener herein claimed, its parts and combinations of parts and all equivalents.

40 Referring to the accompanying drawings in which like characters of reference indicate the same parts in the several views; Figure 1 is a longitudinal sectional view of a pencil sharpener constructed in accordance with this invention; Fig. 2 is a plan view thereof; Fig. 3 is a rear end view thereof; Fig. 4 is a sectional view on the plane of line 4—4 of Fig. 1; and, Fig. 5 is a fragmental view of the upper portion of the pencil sharpener, showing a modified form of thumb grip on the knife slide.

In these drawings 10 represents a casing which is of a tapering or wedge shape as shown with a low front wall 11 and a high rear wall 12 forming a box like frame, the side walls having ears 13 at their upper ends

which are bent around the front wall 11 and the rear wall 12 to hold them in place. The ears 13 may be dispensed with and the end walls held in place in any other desirable manner, but this has been found a desirable construction in practice. At the bottom of the rear wall 12 is a circular opening 14 of a suitable size to receive the end of a pencil, which is shown in dotted lines in Fig. 1.

60 A pencil support 15 is contained within the casing and preferably comprises a block of soft metal, as lead, which may be molded as shown to form a socket the shape of a pencil point, being held in place by means of 70 pins 16 passing therethrough and through the casing and adapted to receive the end of the pencil when entered through opening 14. The pencil support 15 is spaced from the front end 11 of the casing to provide a pocket 75 or receptacle 17 for receiving the shavings, and the rear end of the pencil support is cut away to reduce the weight, leaving an extension 18 for closing the rear space.

75 The upper edges of the side walls of the 80 casing are bent inwardly to form guide flanges 19 which are slightly curved on an arc about a center which is preferably about eighteen inches distant, though an arc of any other radius will do. A slide is mounted on 85 the guide formed by flanges 19 and comprises a lower member 20, an intermediate member 21 and an upper member 22, the lower member bearing beneath the guide flanges 19, the intermediate member being 90 in the same plane with said guide flanges and just fitting therebetween, and the upper member bearing on top of the guide flanges, the three members being secured together by means of rivets 23 or by any other suitable means.

95 The lower member 20 of the slide is provided with a projecting end which is beveled and has a disk shaped knife member 24 mounted thereon, being fitted on a screw 25 100 threaded in the projection and capable of being turned thereon to change its position so as to present a new cutting edge when worn. The upper member 22 has upturned front and rear curved flanges 26 to form a 105 suitable thumb grip to enable the operator to move the slide back and forth in its guide while the device is held in the hand.

110 The upper surface of the pencil support 15 is rounded longitudinally to conform to the curvature of the guide and is rounded transversely to receive the rounded lower cutting

edge of the knife member 24 during its movements, the said surfaces intercepting the socket in the pencil support 15 to form an opening 27 through which the knife member 5 passes during the movements of the slide. When a pencil is within the pencil support the knife member will engage it through said opening and cut a shaving therefrom.

The socket in the pencil support is made 10 conical to fit the pointed end of the pencil and constitute a reinforcement therefor to prevent the point of the pencil being broken, and a lug 28 at the end of said socket constitutes a stop to limit the feeding of the pencil 15 inwardly and to assist in the protection of the pencil point against breakage.

The rear end of the bottom of the casing is knurled at 29 and near the front end thereof it is curved and knurled at 30 to provide 20 gripping surfaces for the fingers and prevent the device slipping in the hand during the operation.

In operation, a pencil is inserted through the opening 14 until it bears in the conical 25 socket of the pencil support 15, and then the slide is moved back and forth in its guide by means of the thumb engaging the thumb hold. With each stroke the knife member 24 cuts a shaving from the end of the pencil 30 where it projects through the opening 27. The pencil may be slightly turned after each stroke of the cutter so that the operation will be uniform on all sides of the pencil and result in a true conical point, the conical 35 socket of the pencil support preventing the lead being broken by the pressure of the knife member thereon and the stop 28 protecting the lead from breakage as the result of any pulling tendency exerted by the knife 40 member thereon. The shavings or chips are forced into the receptacle 17 so that there is no liability of spreading them about or of soiling the fingers with the graphite, and when the operation is completed they may 45 be dumped therefrom. Whenever the cutting edge of the knife member becomes dull it may be adjusted to present a new portion to the work and a new knife member may be easily substituted therefor when the old one 50 is entirely worn out.

The pencil cutter of this invention is convenient for carrying in the pocket and is efficient and durable without involving expensive construction.

55 The flanges 26 of the thumb grip are curved rearwardly to conveniently receive the thumb on either side thereof, so that the pencil sharpener may be used in either hand. As an alternative for this form of thumb 60 grip, the thumb grip shown in Fig. 5 may be used, wherein the top member of the slide is arched to form a half round projection 31 which may be engaged by the thumb on either side.

65 It is obvious that this invention may be

used for sharpening the points of paper covered pencils as well as the end and point of wood covered pencils, it being only necessary to remove the paper to form the tapering end of the pencil as usual and then insert the 70 end of the pencil in the pencil sharpener and cut the graphite thereof to a sharp point as above described.

The guide for the slide may be made straight instead of curved, but it is preferred 75 to arrange it on the curve as here shown, as by doing so the point of the pencil may be made sharper for a given length of cut.

What I claim as my invention is:

1. A pencil sharpener, comprising a sheet 80 metal casing having an opening in its end to receive a pencil, a separate pencil support mounted therein and provided with a conical socket to receive and support the end of the pencil with an opening through 85 which the pencil is exposed, a guide formed by bent edges of the casing, a slide movably mounted in the guide, and a knife member carried by the slide and adapted to engage the end of the pencil through the opening in 90 the socket of the pencil support.

2. A pencil sharpener, comprising a sheet 95 metal casing having an opening to receive a pencil, a separate pencil support contained within the casing and provided with a conical socket to receive and support the end of a pencil with an opening through which the pencil is exposed, a guide formed by inturned edges of the casing, a slide movably mounted in the guide, a knife 100 member carried by the slide and adapted to engage and cut the end of the pencil through the opening in the socket of the pencil support, and a thumb piece on the slide by which the slide may be moved. 105

3. A pencil sharpener, comprising a sheet 110 metal casing having an opening through which a pencil may be inserted, a separate pencil support contained within the casing and provided with a conical socket to receive the end of the pencil with an opening through which the pencil is exposed, a guide formed by inturned edges of the casing, a slide mounted in the guide, a knife member carried by the slide for engaging and cutting the end of the pencil through the opening in the socket of the pencil support, and a pocket formed between the end of the casing and the pencil support to receive the shavings from the knife member. 115

4. A pencil sharpener, comprising a casing having an opening through which a pencil may be inserted, a pencil support contained within the casing and having a conical socket to receive the end of the pencil with an opening through which the pencil is exposed, a guide formed by inturned edges of the casing, a slide comprising a top and bottom plate and an intermediate 125 plate secured together and movably mount- 130

ed to slide on the guide with the inturned edges of the casing held between the top and bottom ^laves, and a rotary knife member adjustably mounted on the lower plate 5 of the slide and adapted to engage and cut the end of the pencil through the opening in the socket of the pencil support.

5. A pencil sharpener, comprising a sheet metal casing having an opening to receive 10 a pencil, a pencil support comprising a block of soft metal contained within the casing and provided with a conical socket to receive the end of the pencil with an opening through which the pencil is exposed, a guide formed by inturned edges of the casing, a slide movably mounted on the guide, a knife member carried by the slide and adapted to engage and cut the end of the pencil through the opening in the socket 15 of the pencil support, and a stop at the end of the opening to engage and support the end of the pencil.

6. A pencil sharpener, comprising a sheet metal casing to receive a pencil, a pencil 20 support contained within the casing and provided with a conical socket to receive the end of the pencil with an opening through which the pencil is exposed, a guide formed by inturned edges of the casing, a 25 slide movably mounted on the guide, a knife member carried by the slide and adapted to engage and cut the end of the pencil

through the opening in the socket of the pencil support, a thumb grip on the slide by which the slide may be moved, and 35 knurled finger grips on the casing to prevent the casing slipping in the hand.

7. A pencil sharpener, comprising a sheet metal wedge shaped casing with bottom side and end walls, lugs on the side walls engaging the end walls, the larger rear wall having an opening therein to receive a pencil, a pencil support within the casing comprising a block of soft metal provided with a conical socket to receive the end of the pencil with 40 an opening through which the pencil is exposed, an inclined curved guide formed by inturned edges of the side walls of the casing, a slide movably mounted on the guide, a rotary knife member carried by the slide 45 and adapted to engage and cut the end of the pencil through the opening in the socket of the pencil support, a lug at the end of the socket forming a stop for limiting the position of the pencil, and a pocket formed in the 50 casing between the end of the pencil support and the end of the casing.

In testimony whereof, I affix my signature, in presence of two witnesses.

ARNE T. PETERSON.
